RAYMOND J. SOUTHWELL, OF NEW ROCHELLE, NEW YORK, ASSIGNOR TO WICKWIRE SPENCER STEEL COMPANY, OF NEW YORK, N. Y., A CORPORATION OF DELAWARE.

COMPOSITE WIRE LATH.

Application filed July 30, 1926. Serial No. 125,860.

This invention relates to a wire lath such as is largely used in building construction as a support for plaster or cement.

It is the general object of my invention 5 to provide a construction in which ordinary woven wire fabric may be made available for such purposes, by combining the wire fabric with a suitable backing sheet of tough paper or other similar sheet material, 10 and by firmly securing the backing sheet to the wire fabric.

A further object is to provide improved 15 stiffening and supporting means for the composite lath, by which the wire fabric and backing sheet will be definitely spaced from a supporting structure, and at the same time the composite lath will be rendered more rigid and better available for the purposes defined.

20 With these and other objects in view, my invention further consists in certain arrangements and combinations of parts which will be hereinafter described and more particularly pointed out in the appended claims.

Preferred forms of the invention are shown in the drawings in which

Fig. 1 is a front view of a portion of my improved composite wire lath;

30 Fig. 2 is a detail sectional view, taken along the line 2—2 in Fig. 1;

Fig. 3 is a partial rear view, showing the means for securing the parts together;

35 Fig. 4 is a view similar to Fig. 1 but showing the use of a different shape of wire mesh;

Fig. 5 is a view similar to Fig. 2 but showing a modified construction to be described;

40 Fig. 6 is a diagrammatic view, indicating the way in which my improved lath is to be used;

Fig. 7 is a sectional plan view, taken along the line 7—7 in Fig. 6; and

45 Fig. 8 is a sectional view of a further modification.

Referring to the drawings, my improved composite wire lath comprises a layer of wire fabric 10, which may be of the hexagonal mesh shown in Fig. 1 or of the square mesh shown at 11 in Fig. 4.

The wires of either form of fabric may be twisted together, as indicated in Fig. 1, or may be formed by securing the wires to

each other by welding or galvanizing, as 55 shown in Fig. 4 or by any other common method.

A backing sheet 12 of strong paper or other similar fibrous material is placed directly against the back of the wire fabric 60 10. Stiffening ribs or elements 13 are placed at intervals against the back of the paper 12, extending from edge to edge of the wire fabric, and preferably of the substantially V-shaped form indicated in Fig. 65 2, the open edges of the V abutting the rear face of the backing 12.

The stiffening elements 13 are preferably 70 secured in place by suitable fastening devices, such as clips or bands 14, as indicated in the drawings. Each of these clips may comprise a strip of sheet metal which embraces one of the stiffening elements 13 and which has its free ends projecting through the backing 12 and clamped about certain elements of the wire fabric 10 or 11.

The parts are thus permanently secured 75 to form a unitary structure which is preferably made up in the form of square or rectangular sheets, ready to be applied to a building structure diagrammatically indicated at 16 (Fig. 7).

The composite sheet will cover a certain 80 number of standard spaces between the studs or supports 16 and is preferably wide enough to overlap to the edges of the studs at each side of the sheet. The other dimension of the sheet may be anything desired, but I have found it convenient to make the sheets of not too great length. The sheets 85 are commonly secured by nails or staples driven through the stiffening elements 13.

When my improved lath is thus secured 90 to a supporting structure, the backing sheet and wire fabric are definitely spaced from the supporting structure by the stiffening elements 13, thus providing a predetermined space back of the composite lath.

When the plaster or cement is thereafter 100 applied to such a composite lath, the paper or backing will be forced rearward slightly away from the wire fabric and sufficiently to permit the plaster to firmly engage the fabric and to be permanently supported thereby. At the same time, however, the 105 backing sheet prevents the forcing of an unnecessary amount of plaster or cement through the screen, thus economizing plas-

ter and preventing the formation of a layer of plaster of unnecessary thickness.

In Fig. 2 I have indicated the sheet 12 of paper or fibrous material as being folded into the V-shaped stiffening element 13, thus providing a pocket 18 to receive a portion of plaster and form an additional tie between the plaster and the lath.

While this construction is desirable, it is not indispensable and I may also use the construction shown in Fig. 5, in which the sheet 12 extends straight across the opening of the stiffening element 13, this latter construction being somewhat easier to manufacture and being sufficiently effective for general purposes.

The dimensions of the wire fabric may be somewhat widely varied, but I have found that either square or hexagonal mesh, with openings of a width of one-half inch or more furnishes a very satisfactory foundation for the support of plaster or cement.

I may also locate the stiffeners 20 between the wire fabric and the paper backing, as shown in Fig. 8, thus providing a definite furring space for the plaster or cement. In this case I preferably provide a second U-shaped stiffening member 23 at the back of the paper backing 22 and secure the parts together by clips 24 encircling both stiffening members 20 and 23 and also portions of the backing 22 and wire fabric 21.

Having thus described my invention and the advantages thereof, I do not wish to be limited to the details herein disclosed otherwise than as set forth in the claims, but what I claim is:—

1. A composite wire lath having, in combination, a sheet of wire fabric, a layer of fibrous sheet material disposed adjacent and immediately in rear of said wire fabric, a plurality of substantially V-shaped metal stiffening strips having their open sides forwardly disposed and abutting the back of said fibrous material, and means to secure said stiffening elements, said fibrous material and said wire fabric permanently together to form a unitary structure.

2. A composite wire lath having, in combination, a sheet of wire fabric, a layer of fibrous sheet material disposed at the back of said wire fabric, a plurality of substantially V-shaped metal stiffening strips having their open sides forwardly disposed and abutting the back of said fibrous material, and clips encircling said strips and extending through said fibrous material and said wire fabric to firmly secure said parts together, said stiffening strips adapted to definitely space said fibrous material from a supporting structure.

3. A composite wire lath having, in combination, a sheet of wire fabric, a layer of fibrous sheet material disposed at the back of said wire fabric, a plurality of substantially V-shaped metal stiffening strips having their open sides forwardly disposed and abutting the back of said fibrous material, and clips encircling said strips and extending through said fibrous material and said wire fabric to firmly secure said parts together, said fibrous material being depressed within said V-shaped strips to form pockets effective to receive portions of the plaster or cement applied thereto.

4. A composite wire lath having, in combination, a sheet of wire fabric, a layer of fibrous sheet material disposed at the back of said wire fabric and spaced therefrom, a plurality of substantially V-shaped inner metal stiffening strips positioned between said wire fabric and said fibrous material, and having their open sides forwardly disposed and abutting the back of said wire fabric, a plurality of U-shaped outer stiffening members secured at the rear of said fibrous material and each adjacent to one of said V-shaped stiffening strips, and clips each encircling an inner and an outer stiffening strip and portions of said fibrous material and of said wire fabric and securing all of said parts together.

In testimony whereof I have hereunto affixed my signature.

RAYMOND J. SOUTHWELL.
